3 Claims. (Cl. 70—456)

ABSTRACT OF THE DISCLOSURE

The present invention relates to a multiple key holder and comprises a plurality of key loops, each key loop having a shank with a head at one end thereof. A support means is provided which has provided therein a plurality of release apertures which receive the shank and are held therein by the head. A closure means is rotatably mounted within the support means such that in one position the closure means will hold the heads of the plurality of key loops within the support means and in another position will open the release apertures to permit the withdrawal of the heads from the support means. A locking means is also provided to hold the closure means in the one position to prevent accidental manipulation of the closure means to its open position.

This invention pertains to key retainers for the support of key carrying loops.

This invention relates generally to key holders, and more particularly it relates to an improved and useful key holder for supporting a plurality of key carrying loops in a suspended manner with means for quickly and conveniently effecting the engagement and release of the loops.

More particularly, this invention relates to and is somewhat in the nature of an improvement upon the disclosure of my previous United States Patent No. 2,575,472 entitled, "Key Holder," issued Nov. 20, 1951. In the key holder as described in the said patent, a plurality of key carrying loops are suspended from a supporting plate formed with slots having enlarged portions through which the heads of the key loops may be passed for removing the loops, and a crank-shaft mounted for rotation on the supporting plate, and provided with a handle at one end and having offset portions adapted in one angular position of the crank-shaft to cover the enlarged portions of the slots to prevent the key loops from being removed, and said crank-shaft being rotatable to another angular position to move the offset portions to uncover the enlarged portions of the slots sufficiently to permit the heads of the key carrying loops to be moved therethrough for removing the key loops.

Various problems arose when attempts were made to construct and use key holders of the above briefly described type which would retain the key loops in their locked position. If the closure means in the form of the crank-shaft was maintained in its established closed position and the key holder in a more or less permanent upright position then the loops as well as the keys secured thereto are prevented from slipping off. But, when the key holder is in a key wallet which is subject to many changes in position, and more especially, if the handle of the crank-shaft is accidentally shifted causing it to rotate to its "open" position the loops have a tendency due to the weight of the keys thereon to fall out of the enlarged openings.

Since, said invention disclosed in my previous application is not provided with positive locking means for

2

retaining the crank-shaft in its closed position the same may be opened by the application of a relatively small force. But, by the provision of a closure member formed to be frictionally engageable with its support housing, a much greater force will be required to rotate the closure member from its normally closed position, wherein the key loops are secured in place to the open position, wherein in said key loops are freely removable.

It is further desirable to provide a locking arrangement between the support member and the closure member when the latter is in its closed position to prevent accidental manipulation of the closure member of its open position. In accordance with the present invention a locking arrangement is provided to retain the key holder in its closed position until the user desires to remove or add any key loops thereto.

In light of the above, an important object of this invention is the provision of an improved key holder having the above noted frictional characteristics for preventing accidental opening of the closure means.

Another object of the invention is the provision of locking means for positively locking said closure member to the supporting member.

Yet another object of this invention is the provision of an improved closure member which may be easily opened by the application of a unidirectional pushing or pulling force and which remains in the position desired without the necessity of the user continually retaining it in said position.

A further object of this invention is the provision of a pair of closure members to permit access to smaller groups of key loops thereby substantially diminishing the number of key loops that can possibly fall out if the key holder is inadvertently rotated while attempting to insert or remove a loop therefrom.

Still another object of this invention is the provision of an improved key loop in which the above described means for positively preventing accidental opening of the key holder is further enhanced.

Other objects of this invention reside in the provision of an improved key holder which is extremely simple in construction, durable and strong throughout long periods of continued use, relatively inexpensive to manufacture, simple and efficient in its operation, and highly efficient in sustaining the above noted objects and purposes.

The above, and other objects, features and advantages of the following detailed description of illustrative embodiments thereof which is to be read in connection with the accompanying drawings forming a part hereof, and wherein:

FIGURE 1 is a top plan view of a key holder embodying the invention;

FIGURE 2 is a front elevational view thereof, with parts broken away and in cross-section;

FIGURE 3 is an enlarged front view in section, of a portion of the closure and support means of FIGURE 2, showing the contacting surfaces therebetween to aid in explaining the present invention;

FIGURE 4 is an end elevational view of the structure shown in FIGURE 2;

FIGURE 5 is a cross-sectional view taken on line 5—5 of FIGURE 2;

FIGURE 6 is a view similar to that of FIGURE 1, but showing a modification of the closure means cooperating with the support means;

FIGURE 7 is a front elevational view thereof, with parts broken away and in cross-section;

FIGURE 8 is a cross-sectional view taken on line 8—8 of FIGURE 7;

FIGURE 9 is a fragmentary front elevational view of the closure handle and support means being shown in interfitted locked relationship to each other, the closure means being shown in its closed position;

FIGURE 10 is an end elevational view of the locking structure shown in FIGURE 9; with a portion thereof broken away and in cross-section.

FIGURE 11 is a view similar to that of FIGURE 9, but showing a modification of the locking arrangement between the closure and support means;

FIGURE 12 is an end elevational view of the locking structure shown in FIGURE 11; with a portion thereof broken away and in cross-section;

FIGURE 13 is an enlarged front elevational view of a key loop in accordance with the present invention;

FIGURE 14 is an end elevational view of the structure shown in FIGURE 13.

Referring to the drawings in detail and initially to FIGURES 1 through 5 thereof, it will be seen that a key holder embodying the present invention, may be generally identified by the reference numeral 10, comprises a supporting member or plate 12, a closure member or crank-shaft 40 mounted for rotation therewith, and a plurality of key carrying loops or hooks 50 swingably mounted on the supporting plate.

The supporting plate 12 comprises a lower generally flat wall portion 13 and an upper portion 14 consisting of a plurality of spaced apart upright fingers extending from and integral with the upper edge 28 of the lower portion 13 of the supporting member 12. A pair of end fingers 15 extend from each end of the lower portion 13 and at least one intermediate finger 16 is provided between said end fingers 15. The intermediate fingers 16 also may be integral with and extend from the upper edge 28 of the lower portion 13 of the supporting member.

The fingers 15 comprise a forwardly and upwardly curved portion 17 from which extends a rearwardly and upwardly inclined portion 18 terminating in a rearwardly and downwardly extending ear portion 19 to form an aperture 20 (FIGURE 4) for receiving the closure member 40.

The intermediate fingers 16 are constructed such that the end fingers 15 are comprised of a forwardly and upwardly curved portion 22 from which extends a rearwardly and upwardly inclined portion 23 terminating in a rearwardly and downwardly extending ear portion 24 to form an aperture 25 (FIGURE 5) for receiving the closure member 40. The apertures 20 and 25 are in longitudinal alignment with each other and are formed as such to provide a substantially cylindrical bearing surface for passage therethrough of the closure member 40. The apertures 20 and 25 being positioned with respect to the flat wall 13 such that a portion of the closure member 40 may contact said wall 13, as shown in FIGURE 4.

The fingers 15 and 16 are thus in aligned spaced relationship and are integrally joined together at one end thereof and terminating in a substantially closed ear portion to define the apertures 20 and 25 respectively. The fingers (15, 16) are spaced apart to define a plurality of transversely extending slots 27 which extend from the upper edge 28 of the lower portion 13 of the support member 12 until the end of the fingers 15 and 16 and are of a width to pass the shank 55 of the key loop 50 but not the head 51 thereof.

The upper end of the slots 27 are provided with release apertures 30 which are formed by notches or cutouts 31 formed at each intermediate finger 16 and the corner of the end fingers 15 facing the slot 27, the purpose of the release apertures 30 will hereinafter be described more fully.

The key carrying loops 50 each comprise a shank 55, a bent back looped portion 56, and an enlarged anchoring head 51 at the upper end of the shank 55. As shown in FIGURE 2, the shank 55 of each loop 50 passes through

one of the slots 27. The shanks 55 and the bent back portions 56 normally lie against the front of wall 13 and the heads 51 engage the inner surfaces of the curved portions 17 of the fingers 15 and 16. Thus, the key carrying loops 50 can swing within the slots 27, but are suspended by means of the enlarged heads 51. The loops 50 may be swung forwardly and upwardly for use as for insertion of one or more keys within the looped portion 56, as by moving loops 50 along their respective slots 27, but they are retained by the supporting plate 12 during this process.

10 The closure member 40 comprises releasable means for preventing removal of the key carrying loops 50, while permitting said loops to swing. To this end the closure member 40 extends lengthwise through the apertures 20 and 25 defined by the ear portions 19 and 24 of fingers 15 and 16 respectively, and is rotatable therein from a normally closed position to block the release apertures 30 to an open position to permit the release of the loop head 51 therethrough. The closure member 40 is continuously 15 biased against the walls 33 and 34 defining apertures 20 and 25 to provide frictional engagement therebetween thereby requiring a positive force to be applied to the closure member 40 for rotation thereof.

The closure member 40 may be stamped or formed 20 from a strip of wire into the desired shape (FIGURES 1, 2 and 3), which is shown to be provided with a series 25 of inverted curved sections 41 and 42 integral with each other and terminating at one end thereof in a handle portion 43 with an eyelet shaped end 44 at one end thereof and 30 in a substantially straight section 45 at the opposite end thereof. The curved sections 41 are positioned co-extensively within the ear portions 24 and the curved sections 42 within the slots 27. The curved sections 41 are formed 35 to have a curvature which when situated within apertures 25 and/or 20 will frictionally engage the inner wall 34 of the ears 24 and may also engage the wall 33 defined by ear 19 of the end fingers 15. As illustrated in FIGURE 3 the curved section 41 has essentially three contacting surfaces which frictionally engage the wall 34 at points F 40 to thereby continuously bias the closure member 40 as if it were acting as a spring. By providing a closure member 40 that is continuously biased a positive force is required 45 to rotate the closure member 40 when the handle 43 is engaged either accidentally or intentionally. Additionally the closure member 40 will remain in the position selected by the user and this is of particular importance when a key loop 50 is being engaged or disengaged from the key holder 10. Once the closure member 40 is rotated to its open position the user will have both hands free to accomplish his desired task of manipulating the key loop.

50 Thus, the curved sections 41 situated within the ears 24 are contoured to engage the inner wall 34 of said ears 24 irrespective of the closure member's 40 position and in this manner a continuous frictional force is encountered 55 by the user when an attempt is made to rotate the closure member 40.

The sections 42 of the closure member 40 contained 55 within the slots 27 are preferably formed having a curvature to block the release apertures 30 when the closure member 40 is in its closed position, thereby simultaneously closing the closure apertures 30 of the slots 27 to prevent the heads 51 of the hooks 50 from moving through the release apertures 30 of these slots 27, and thereby retaining the key carrying loops 50 on the supporting plate 12. 60 The offset handle 43 which has a curved portion 44 is adapted to contact the front of the flat wall 13 when the closure member is in its locking position. Thus, when the closure member 40 is in its locking position, the handle 43 projects downwardly whereas, the curved portions 42 project forwardly, as shown in FIGURE 3.

65 The fingers 15 and 16 which terminate in curved ear portions 19 and 24 forming the bearing walls 33 and 34 respectively, are preferably in longitudinal alignment with each other to rotatably guide and frictionally engage the 70 closure member 40 positioned therethrough.

As shown in FIGURES 1 and 2 the slot 27 is not necessarily equal in width to that of the upper terminal portions 21 and 26 which terminate in the ears 19 and 24 respectively. The criterion is that the curvature of the sections 42 be sufficient to block the release apertures 30 when the closure means 40 is in its closed position and to permit release of the key loop 50 when said closure means 40 is rotated upwardly approximately 180 degrees.

When the closure member 40 is rotated to its open position, as shown in FIGURE 7, and will hereinafter be explained with respect thereto, the curved section 42 is rotated to a position which permits the heads 51 to be lifted out of slots 27 and through release aperture 30 to be completely clear of the key holder 10.

In the above described key holder 10, the closure means 40 consisted of one closure member 40, however, as shown in FIGURES 6, 7 and 8 a key holder 10a which is generally similar to the key holder 10 and has parts identified by the same reference numerals employed in connection with the corresponding parts of key holder 10, but with the letter *a* appended thereto, is provided with a pair of symmetrical closure members 40a extending along the longitudinal axis formed by the apertures 20a and 25a.

The average key holder is generally manufactured to accommodate about six to eight key loops and in the embodiment 10 of the present invention the entire closure member 40 has to be rotated from its closed to open position to gain access to insert or remove a key loop. Although the present invention permits the user to have both hands free for manipulation of the key loop 50 since the closure member 40 will remain in its open position due to the frictionally designed characteristics inherent therein, there is always the possibility that the user will tilt the key holder 10 in its open position thereby causing all the loops 50 to fall out. To alleviate his problem a pair of closure members 40a are employed and are generally similar to closure means 40 except that they contain a lesser number of inverted curved portions 41a and 42a. Each of the closure members 40a comprise releasable means for preventing removal of the key carrying loops 50a, while permitting said loops to swing.

Each closure member 40a extends lengthwise through the apertures 20a and 25a defined by the ear portions 12a and 24a of fingers 15a and 16a respectively, and is rotatable therein from a normally closed position to block the release apertures 30a to an open position to permit the release of the loop head 51a therethrough. The closure members 40a are continuously biased against the walls 33a and 34a defining apertures 20a and 25a to provide frictional engagement therebetween to require a positive force to be applied to the closure member 40a for rotation thereof.

The inverted curved sections 41a and 42a are integral with each other and terminate at one end thereof in a handle portion 43a with eyelet shaped end 44a at one end thereof and in a substantially straight section 45a at the opposite end thereof. The closure members 40a face each other and terminate in an intermediate finger 16a (FIGURE 7) and are each individually operable with respect to the support plate 12a.

Another advantage of providing a pair of closure members 40a is the ability to increase the biasing load or frictional resistance between the contacting surfaces associated with each closure member 40a and simultaneously maintain the force to be applied for rotation of the closure member the same as when one closure member per key holder is employed. One reason for this is that since there are fewer contacting edges or surfaces on the closure member they can each sustain an increased loading per contacting surface.

As illustrated in FIGURES 6 and 7 the closure members 40a may be operated independently of each other and wherein one may be in its opened position, the other may be in its closed position. This flexibility permits the

user to gain access to a select grouping of key loops 50a for either the removal or insertion within the key holder 10a of said loops 50a with the chance of fewer loops falling out. The key loop 50a is removed from the key holder 10a by firstly rotating the closure member 40a associated therewith to its open position. Key loop 50a is secondly pivoted to a substantially horizontal position as seen best in FIGURE 8 and thirdly moved in a vertical direction until its head 51a exists through the release aperture 30a. To insert a key loop the process is essentially reversed.

Although the above described positive restraining means between the closure and support means substantially reduces the potential accidental manipulation of the closure means to its open position a locking arrangement is herein provided to further safeguard the user from such an occurrence. The locking arrangements illustrated in FIGURES 9 through 12, and hereinafter to be described in detail, may also be employed with a key holder that is not provided with any positive restraining means between the closure and support means.

As shown in FIGURES 9 and 10, a key holder 10b which may be generally similar to the previously described key holders 10 and 10a and which has its several parts identified by the same reference numbers as have been used in describing the corresponding parts of the previously described key holders, is provided with a locking arrangement to provide positive engagement between the closure member 40b and support plate 12b. The closure member 40b of the present invention may be formed from a steel or aluminum wire, and the latter may vary in diameter depending upon the metal used and the degree of resiliency desired. The handle portion 43b terminates in a looped eyelet end 44b which has a leg 46 extending angularly therefrom and in a direction towards the lower portion 13b of the supporting plate 12b.

To accommodate the leg 46 a raised flared projection 47 extending from the lower portion 13b of the support plate 12b and having a receiving recess or aperture 48 to define a bearing surface for frictionally engaging the leg 46 when the latter is in the closed position illustrated in FIGURE 10 is provided. The eyelet end 44b preferably has a region thereof which exceeds the limit defined by the support member 12b (FIGURE 9) to permit the user to grasp the eyelet end 44b of the closure handle 43b and pull it upwardly to rotate the closure member 40b to its open position. When the leg 46 is forced down into its engaging position, the leg 46 is snugly engaged with the bearing surface of recess 48 of the flared projection 47. The leg 46 thus firmly engages the support member 12b in the manner of a clamp to prevent accidental disengagement thereof.

FIGURES 11 and 12 illustrate a key holder 10c which may be generally similar to the previously described key holders 10 and 10a, and which has its several parts identified by the same reference numerals as have been used in describing the corresponding parts of the previously described key holders, but is provided with a locking arrangement of another design as to that illustrated in FIGURES 9 and 10.

A raised projection 52 having an outer bearing surface 53 is integrally connected to the lower portion 13c of the support member 12c and extending outwardly therefrom and in the direction of the closure member 40c. The handle portion 43c of the closure member 40c terminates in an eyelet end section 44c having an inner bearing surface 54 to frictionally engage the outer bearing surface 53 of the raised projection extending from the support member 13c. The eyelet section 44c firmly engages the raised projection 52 to prevent accidental opening of the closure member 40c.

It will be recognized by those skilled in the art that the hereinabove described locking arrangements provide not only the desired locking feature but also coincidentally provide a visual warning as to whether or not the

key loops 60, in any of their various forms, are locked into position on the supporting plate 12. It may be seen that when the closure member 40, is in the downwardly facing position the key loops 60 are closed into the locked position and the position of the closure member 40 in relation to the support plate 12 will visually indicate whether or not the key loops 60 are locked into position.

The desirability of easily removing or inserting a key onto the key loop is present irrespective of the other features of the key holder. The key loop 60 illustrated in FIGURES 13 and 14 may be used in combination with any of the illustrated embodiments of the present invention and is essentially a key loop that has the additional safeguard of requiring a positive force to be applied thereto to separate the overlapping edges for insertion or removal of a key therefrom.

Depending from the key loop head 61 are a pair of arm members. The first arm member or shank 62 consists of the upper substantially straight section 64 and rigid restraining member 66. The second arm 65 is provided with an upper section 63, which is joined to the underside of the key loop head 61 with the first arm member or shank 62, and is integral with and merges into an outwardly curved portion 67 and an upwardly and forwardly curved portion 68 terminating in an elongated edge 69. The rigid restraining member 66 is integrally joined by its upper portion 64 to the head 61 and its opposite end merging into a curved portion 70 which curves towards the arm 65 and terminates in an elongated edge 71.

The elongated edges 69 and 71 are designed and may have a flat or concave cross-section to fit within each other and to resist the outward pressure of the arm 65. The key loop 60 of the present invention is contoured to specifically take advantage of tension obtained when the arm 65 is formed with its upwardly curved portion 68 in the form of the uncompleted loop about half an inch or more from where it merges at the base 67 so that its elongated edge 62 is made to press under but against the curved portion 70 of the rigid restraining member 66. The restraining member 66 may be made about three-quarters of an inch in length with its curved portion to enclose the overlapping free end of the arm 65 for a distance of about one-quarter of an inch. In this arrangement the shorter rigid restraining member 66 may be on either side of the elongated edge 69 of the arm 65.

With this arrangement of elements the stress normally built up beneath the key loop head 61 flows from the head itself into the two arms, and the opposing stresses of the rigid restraining member 66 and elongated edge 69 require a positive force to overcome the said forces. In a removable keyholder it is a further advantage, by way of adding a form of security, to provide a type of loop from which a key may easily be removed without extracting the loop from the keyholder per se.

While in accordance with the patent statutes, preferred embodiments of the present invention have been illustrated and described in detail, it is to be particularly understood that the invention is not limited thereto or thereby.

I claim:

1. A key holder comprising a plurality of key loops, each loop being provided with a shank having a head positioned at the end of the latter, support means removably suspending said key loops therefrom, said support means including a plurality of spaced fingers integrally joined together at one end and terminating in a substantially closed ear at the opposite end to define an aperture, the aperture of said ears being in substantial longitudinal alignment with each other, said fingers being spaced apart to define a plurality of transversely extending slots, each slot being of a width to pass the shank of the key loop but to retain the head thereof, each of said slots being provided with a release aperture, said release

aperture being large enough to pass the head of the key loop, and closure means extending lengthwise through the apertures defined by said ears and rotatably therein from a normally closed position to block said release apertures to an open position to permit the release of said loop heads through said release apertures, said closure means including a series of curved sections connected to each other and terminating at one end thereof in a handle portion, said curved sections being provided with contacting surfaces for frictionally engaging the surface of at least one of the apertures defined by said ears to thereby require a positive force to be applied to said closure means for rotation thereof, a locking means for securing said support means to said closure means when the latter is in its closed position to prevent accidental manipulation of the closure means to its open position, said locking means including a raised projection having a bearing surface, said raised projection extending from said support means and adapted to frictionally engage the handle portion of the closure means with its bearing surface, said handle portion being formed with an eyelet section adapted to fit around said projection.

2. A key holder comprising a plurality of key loops, each loop being provided with a shank having a lead positioned at the end of the latter, support means removably suspending said key loops therefrom, said support means including a plurality of spaced fingers integrally joined together at one end and terminating in a substantially closed ear at the opposite end to define an aperture, the aperture of said ears being in substantially longitudinal alignment with each other, said fingers being spaced apart to define a plurality of transversely extending slots, each slot being of a width to pass the shank of the key loop to retain the head thereof, each of said slots being provided with a release aperture, said release aperture being large enough to pass the head of the key loop, and closure means extending lengthwise through the apertures defined by said ears and rotatably therein from a normally closed position to block said release apertures to an open position to permit the release of said loop heads through said release apertures, said closure means including a series of curved sections connected to each other and terminating at one end thereof in a handle portion, said curved sections being provided with contacting surfaces for frictionally engaging the surface of at least one of the apertures defined by said ears to thereby require a positive force to be applied to said closure means for rotation thereof, a locking means for securing said support means to said closure means when the latter is in its closed position to prevent accidental manipulation of the closure means to its open position, said locking means including a recess located on the support means, and a raised projection extending from the handle of the closure means and adapted to frictionally engage said recess.

3. A key holder comprising a plurality of key loops, each loop provided with a shank having a head positioned at the end of the shank, support means to removably suspend said key loops therefrom, said support means including a plurality of spaced apart fingers integrally joined together at one end thereof and terminating in a substantially closed ear at the opposite end to define an aperture, the apertures of said ears being in substantial longitudinal alignment with each other, said fingers being spaced apart to define a plurality of transversely extending slots, each slot being of a width to pass the shank of the key loop but to retain the head thereof, each of said slots being provided with a release aperture, said release aperture being large enough to pass the head of the key loop, closure means extending lengthwise through the apertures defined by said ears and rotatably therein from a normally closed position to block said release apertures to an open position to permit the release of said loop heads through said release apertures, said closure means being continuously biased against the walls defining said apertures defined by said ears to provide fric-

tional engagement therebetween to require a positive force to be applied to said closure means for rotation thereof, locking means for securing said support means to said closure means when the latter is in its closed position to prevent accidental manipulation of the closure means to its open position, said key loops are provided with a pair of arm members depending from said head, one of said arm members defining a rigid restraining member, said rigid restraining member including a comparatively straight portion connected to said head and a curved end portion extending towards the other arm and terminating in an elongated edge, said other arm including a comparatively straight portion connected to said head, an outwardly curved intermediate portion and an upwardly and forwardly curved end portion having an elongated edge terminating inwardly of and overlapping said elongated edge of said restraining member in side by side relationship, said overlapping elongated edges being separable by applying a positive force to said upwardly and forwardly curved end portion.
